UNITED STATES PATENT OFFICE.

MARSHALL C. LEFFERTS, OF NEW YORK, N. Y.

DESIGN FOR A COMB, &c.

SPECIFICATION forming part of Design No. 25,119, dated February 4, 1896.

Application filed December 18, 1895. Serial No. 572,600. Term of patent 7 years.

To all whom it may concern:

Be it known that I, MARSHALL C. LEFFERTS, a citizen of the United States, residing in the city, county, and State of New York, have invented and produced a new and original Design for Combs and the Like, of which the following is a specification.

This invention relates to a design for combs, as shown in the accompanying illustrations, wherein—

Figure 1 is a side elevation; and Fig. 2, a sectional elevation on the line $x-x$, Fig. 1.

The essential feature of my design resides in the surface ornamentation, as shown.

The general configuration of the comb is rectangular, and it is provided with the conventional teeth, as shown.

The upper portion 1, or what is termed the "back" of the comb, is provided on each verti-

cal side with an ornamentation consisting of the ribbon 2, formed of raised and depressed curved segments 3 4, and a central bar 5, about which the ribbon appears spirally disposed.

As will be seen in Fig. 2, the bar 5 appears to pass through the raised segments 3.

The top of the back is flared out, as at 6, and between the upper edge of the back and the range of segments 3 the back is provided with straight channel or groove 7.

I claim—

The design for a comb and the like, substantially as herein shown and described.

Signed in the city, county, and State of New York this 16th day of December, 1895.

MARSHALL C. LEFFERTS.
